WILLET C. WELLS AND FRANK E. WELLS, OF COLUMBUS, OHIO.

PROCESS OF AND APPARATUS FOR BREAKING UP THE COMPONENTS OF PETROLEUM AND THE LIKE INTO MORE VOLATILE PRODUCTS.

Application filed August 10, 1920. Serial No. 402,536.

Our invention relates to improvements in the process of, and apparatus for breaking up petroleums and the distillates and residues of petroleums and the like which are 5 not sufficiently volatile to be classed as motor spirits or gasoline, and by the practice of our invention we convert a great portion of such materials into the equivalent of natural gasoline with no liquid residue; the 10 remainder of such materials is commercial illuminating gas and carbon.

The current method of breaking up hydrocarbons is to subject them to pressure in a still containing a large quantity of 15 hydrocarbons, to raise the boiling point to the temperature necessary to decompose the same. But there are vital objections to this treatment, namely,—when a considerable body of hydrocarbon is raised to a high 20 temperature under great pressure in a still, a very hazardous condition is created; also, the carbon produced in the process rapidly coats the still bottom and thus insulates it to such an extent that the degree of heat to 25 which the still bottom is subjected to produce proper results greatly weakens the still bottom, so that the limit of safety is reached by the time half of the charge is driven off; and from this fifty per cent taken off not 30 more than fifty to fifty-five per cent will make marketable gasoline, while the remaining seventy or more per cent of the original charge must be used for other purposes and at a lower market value than when it was 35 placed in the still. Consequently, there must under present conditions be an excessive margin between the cost of gasoline and the cost of the materials used to produce gasoline. Still further, the bituminous 40 matter in residue fuel oils and like heavy hydrocarbons coats the still bottom so quickly with carbon in this current method of treatment as to prohibit their use in the production of gasoline therefrom.

45 Many attempts have been made to improve the method above described for the utilization of all the marketable portions of hydrocarbons; among these is the method of submerging the hydrocarbon in a permanent fluid bath of sufficient gravity to float the carbon formed in the process, such bath being usually molten lead, and the hydrocarbon is submerged therein in a still. Other experimenters submerge the hydrocarbon in heated lead contained in pendant 55

tubes or pockets opening out of the still bottom, of such length that the weight of the lead at the bottom of the column of which the hydrocarbon is introduced is regarded as an important pressure feature. 60

These and other methods have been and are being tried but we have found serious objections to them all which render their use for commercial purposes practically prohibitive. We have found that carbon will 65 form and soon clog an unprotected tube or pipe which conveys the hydrocarbon to submergence in the lead bath having a sufficient temperature to break up the hydrocarbons being treated; also that hydrocarbons decomposed in such bath will deposit carbon mixed with sufficient bituminous matter to envelope and retain the spray of the violently bubbling lead, and thereby rapidly form cakes of coke permeated with 70 lead, and these rigidly attach themselves to the sides of the still and the tubes through which the hydrocarbon is introduced. This lead filled coke, when cold, resembles a sponge filled with set cement. We have also 75 found that the difference in the extent of the expansion of the lead and the metal pocket or tube containing the lead, at the degree of heat required in the process, is so great that the tube is certain to rupture as readily 80 as if water were frozen therein. Further, if the hydrocarbon is left in the tube or pipe through which it is introduced into the bottom of the liquid bath, at the close of operation, the heat of the bath will break up the 85 hydrocarbon thus remaining in the tube and will soon close the said tube with carbon at the top of the bath. These discoveries of ours have shown that motor spirits can not be successfully produced with the methods 90 described as in current use; therefore the conception that the mere submergence of hydrocarbons in a sufficiently heated permanent fluid bath of sufficient gravity to 95 float the carbon formed, is an open door to 100 successful commercial operation, is quite delusive.

Our improvements create a process which avoids all the objections above outlined and is thoroughly adapted to commercial use, 105 and the apparatus shown in the drawings presents a satisfactory embodiment of our invention. Referring to the drawings which are hereto attached and are hereby made a part of this specification, Fig. 1, is a vertical 110

sectional view of the cracking apparatus, showing the burners, connections for admitting compressed gas into the tubes or pipes through which the hydrocarbon passes to 5 submergence for the purpose of displacing the hydrocarbon remaining therein at the close of operation, the condenser, the supply tank, the tank which receives the mixed carbon and hydrocarbon from the retort or 10 still, and the press wherein the carbon is separated from the hydrocarbon. Fig. 2 is an enlarged sectional view of one of the pendant tubes or pockets, designated at 3. Fig. 3 is an enlarged sectional view of a 15 thermostat; Fig. 4 is a cross section along the line A—A of Fig. 2, showing the detailed construction of the hydrocarbon inlet tube or pipe and its casings or coverings designated for its protection against the 20 heat, as above mentioned.

The description of the apparatus will now be given in describing the operation thereof in the performance of our process. 1 is the still and 2 is the furnace having two burners 25 therein, shown at 38 and 39; 38 is the upper one which is used at the beginning of operations to heat the lead 4 contained in the pendant closed tubes or pockets 3 at the upper open end thereof, whereby the lead is 30 permitted to expand into the bottom of the still and rupture of the pendant tube is avoided. The heat from burner 38 is applied to the bottom of the still also, and the lead bath therein is heated at the same time 35 as the lead in the pendant tubes. The heating of the lead in the pendant tubes proceeds from the top downwardly, and when this is sufficiently accomplished the burner 39 is started and 38 is shut off, and the heat thereafter needed in the operation is supplied 40 from burner 39.

In filling the pendant tubes 3 with lead they are poured full and the lead is permitted to run over the top and spread over 45 the bottom of the still, and hence the lead bath in the still and in the pendant tubes or pockets is a continuous body, and is brought to a uniform degree of heat as described. The lead bath on the still bottom is shown 50 at 5.

6 is the still covering or cap through which is fitted the tube 7 having its lower end closed, and thereinto is inserted the pyrometer point 10, having the usual electric 55 connections; the point 10 is inserted to reach to the bottom of the tube 7 which extends into the lower portion of the pocket or pendant tube 3. 8 is the casing containing the hydrocarbon inlet tube 12, and the construction thereof is most clearly shown in Fig. 4; tube 12 is encased by tube 8^b which in turn is provided with an asbestos jacket 8^a, which is encased within the outer tube 8, and by means of these coverings the inner tube 12 60 through which the hydrocarbon is delivered

into the bottom of the lead bath in the pendant tube 3, is protected against the heat in the body of the still and the hydrocarbon can thus be introduced into the bottom of the lead bath before decomposition takes place. 70 9 is a tube with its lower end closed, also inserted into the bottom of the lead bath in the pendant tube 3, and enclosing the thermostat tube 11, which is inserted thereinto until it reaches the bottom thereof. In Fig. 75 2 it clearly appears that the pyrometer point, the thermostat tube and the inlet tube for the hydrocarbon, all extend nearly to the bottom of the lead bath in the pendant tube or pocket 3, and hence all are subject 80 to the degree of heat there prevailing, where the hydrocarbon first becomes subject to the decomposing influence of the heat; it is also noticed that these encasing tubes described are positioned alike in the lead bath 5 in the still, and throughout their lengths are subject to exactly the same heat conditions.

The hydrocarbon treated in the operation is shown in a tank at 13 from which it is pumped, at the beginning of the operation, 90 through pipe 15, the valve 15^a being closed, through valve 31^a into pipe 31, into pipe 25 until it overlies the lead bath 5 in the bottom of the still and overflows through pipe 27, leaving a body of hydrocarbon indicated 95 at 26 in the still at the time the operation is begun. Thereupon valve 31^a is nearly or quite closed, valve 15^a is opened, and the pumping continues and the hydrocarbon 100 flows on through pipe 15 into pipe 16 and so into the chamber 17^c of the thermostat box 17. Within box 17 is the diaphragm 35 carrying the valve stem 36 with the tapered valve 36^a at the end thereof, projecting through the opening in the wall 17^b; the valve 36^a is engaged by the spring 36^b whose tension is fixed by the screw 17^a adjustable from the outside of the box 17. The behavior of the apparatus here described is as follows:—The air in the thermostat tube 11 110 is expanded by the heat prevailing in the lead bath at the bottom and throughout the extent of the pocket or tube 3, and the expansion increases until it is sufficient to press inwardly the diaphragm 35 against the pressure exerted thereagainst by the hydrocarbon introduced into the box through pipe 16 as described, and also against the tension of the spring 36^b upon the valve 36^a. Thereupon 115 the hydrocarbon flows into tube 12 through valve opening at 36^a, and passes on down through the tube 12 into the lead bath at the bottom of the pendant tube or pocket 3 as clearly appears in Fig. 2. When the incoming hydrocarbon has entered in quantity 120 sufficient to influence the degree of heat prevailing therein so as to lessen the expansion of the air in the thermostat tube, diaphragm 35 will retreat towards its normal position 125 and partially cut off the inflow of hydrocar- 130

bon, depending upon the heat conditions existing in the pendant tube 3, thus automatically establishing conditions of thermal equilibrium in the lead bath.

5 The weighted valve 39^a on the bypass 40 from tank 13 to pipe 15 assures uniform pressure in the chamber 17^c of thermostat box 17 regardless of the volume of the hydrocarbon introduced thereinto. When the 10 first hydrocarbon is admitted through the thermostat box as above described, it enters the tube 12 with pressure of 10 pounds or enough to expel from the lower end of said tube 12 of 19 inches length the lead therein 15 and drive it out into the surrounding body of the lead, and thereupon the hydrocarbon issues in a fine stream into the lead bath at the bottom of tube 3; the vapor from the hydrocarbon ascends through the lead bath 20 and violently agitates the lead into uniform temperature throughout. Thus, on account of the columnar form of the lead bath in the pendant tubes the vapors are kept long enough within the body of the lead bath in 25 their passage therethrough to subject them all alike to a uniform decomposing temperature; varying with different hydrocarbons from 850 to 1175 Fahr. As these vapors rise through the overlying hydrocarbon they deposit the carbon produced in the operation 30 therein, where it becomes thoroughly mixed therewith by the violently bubbling lead. The vapors pass from the retort through pipes 18 and 19 and through vapor line 35 19^c to the aerial condenser; the condensate in the first section 20 is returned through pipe 24 and pipe 25 to the still. The vapors condensed in the succeeding sections 21 and 22 are trapped off at 32 and 33 to their 40 respective containers, the portions which are sufficiently volatile for use are evaporated therefrom and the remainder is returned to tank 13 in a manner not necessary to be shown herein, for a repetition of the operation. The fixed gas and vapors passing section 45 22 pass on through water cooled section of condenser 23 and the condensate is trapped off at 34, being motor spirits; the fixed gas is conveyed away through the pipe 50 37 and may be subjected to compressing or absorptive process to obtain light oils therefrom.

If the condensate from section 20 should be insufficient to supply the volume of hydrocarbon necessary to carry out the carbon produced in the still, valve connection 31^a can be opened to admit hydrocarbon from tank 13 to maintain an overflow through pipe 27 into tank 28; thence the mixture 55 of carbon and hydrocarbon drawn off continuously from the surface of the lead bath in the still is pumped into press 29; here the carbon is retained in cakes, and the hydrocarbon is returned through pipe 30 to tank 13 whence it is pumped into the still 60

for treatment by submergence in the lead bath, as described. When the flow of hydrocarbon into the lower portion of pendant tubes 3 ceases for any reason, valve 15^a is closed, and valve 15^b is opened; a supply of compressed gas is then admitted through pipe 15^c into pipe 15 and into the tubes 16, through the thermostat box into pipes 12, and thereby the hydrocarbon remaining therein is expelled out into the lead bath, 75 and the deposit of carbon therein, mentioned hereinabove, is prevented.

To summarize our improvements we may set forth the features as follows, to emphasize the contrast with current methods:—

By means of tubes or pockets pendant from the still we obtain the maximum heating surface, and by the use of molten lead or its equivalent in said tubes and covering the floor of the still carbon is prevented from adhering to the heating surface; by melting the lead in the tubes upon beginning the operation, from the top downwards, rupture of the tubes from the unequal expansion of the lead and the tube body is prevented; by insulating or protecting the hydrocarbon inlet tubes as described, the stream of hydrocarbon passes through the tubes without evaporating therein, and consequently the formation of carbon in said tubes is prevented; such formation would close the tubes and of course interfere with successful operation. By introducing the hydrocarbon to be broken up into the lead at the bottom of said tubes, heat is taken up and the lead is violently agitated by the vapors from the hydrocarbon, and thus the lead, by convection, becomes a medium to transfer uniform temperature to the hydrocarbon injected thereto and the vapors therefrom in their rise through the depths of the heated lead in the pendant tubes; and by means of thermostat control of the volume of hydrocarbon entering each tube, equilibrium of temperature is maintained therein between the heat absorbed in breaking up the hydrocarbons and the heat applied to the hydrocarbon; the vapors in their passage through the body of the hydrocarbon overlying the lead bath on the floor of the still, deposit the carbon they carry therein, and it is thoroughly mixed with the hydrocarbon by the violent ebullition of the lead, and this mixture is caused to flow continuously from the still by the continuous introduction of a supply of hydrocarbon into the still above the lead floor; the mixture is treated in the press whereby the carbon is separated in cakes and the residue passes on to the hydrocarbon tank to be pumped into the still for submergence in the lead bath as described above. The condensate derived from this process which is not sufficiently volatile and homogeneous for gasoline has its light portion evaporated off, and the residue is 130

returned for further breaking up as described; the final products are commercial gas, gasoline and carbon.

What we claim is:

- 5 1. The process of converting hydrocarbon oils into more volatile products which consists in submerging said hydrocarbon oil for vaporization and decomposition beneath a molten metal bath contained in a retort, 70
 10 withdrawing the resulting vapors and gases from the upper part of the retort, conveying them away and condensing them, maintaining a continuously moving body of hydrocarbon oil on the surface of said molten 75
 15 metal bath, continuously removing said body of hydrocarbon oil from the retort, separating therefrom carbon resulting from the decomposition, and returning the body of oil to the retort for submergence beneath the 80
 20 molten metal bath.
2. The process of breaking up hydrocarbons into more volatile products by submerging them for decomposition in a heated molten metal bath which consists in protecting incoming streams of hydrocarbon against 85
 25 decomposing temperature in the ducts through which they are introduced into said bath, subjecting the said hydrocarbon to the heat of said bath, subjecting all of the 90
 30 vapors thus produced to uniform degree of heat in their passage through said bath to the surface thereof, and expelling all hydrocarbon from said ducts when operation ceases by the introduction into said ducts of 95
 35 compressed gas.

3. The process of converting hydrocarbon into more volatile products, which consists in submerging said hydrocarbon for decomposition into a column of heated molten 100
 40 metal bath by introducing said hydrocarbon into the lower portion of said column; protecting the hydrocarbon from decomposition by heat in their course to submergence; controlling the temperature of the said column of molten metal by automatically controlling the volume of hydrocarbon being introduced thereinto; maintaining a continuously moving body of oil on the surface of said metal whereby the carbon resulting 105
 45 from the decomposition is continuously removed from the system.

4. The process of breaking up hydrocarbons into more volatile products which consists in submerging said hydrocarbon by introduction thereof in streams through heat protected tubes into heated columns of a molten metal bath contained in tubes suspended from the bottom of a retort, vaporizing and decomposing said hydrocarbon in 110
 50 said bath, allowing the vapors thus produced to rise and pass through a body of hydrocarbon overlying said bath and kept at a lower temperature than the decomposing temperature of the bath in said columns by 115
 55 the return thereinto of the condensate of the

less volatile portion of the vapors produced in the process, mixing the carbon formed by the operation with said body of hydrocarbon by the passage of vapors therethrough, and continuously trapping off the mixture of 70
 carbon and hydrocarbon thus produced.

5. In the cracking of hydrocarbon oils the described process consisting in passing the oil to be treated before it has become evaporated or dissociated through a molten metal 75
 bath in a retort, collecting the resulting vapors and gases in the upper part of the retort, conveying them away and condensing them, continuously supplying directly to and withdrawing directly from the surface of 80
 the bath a layer of the heavy fractions and unvaporized hydrocarbons which holds the carbon impurities in suspension, regulating the supply of the material to form said layer as required and separating the carbon. 85

6. In the cracking of hydrocarbon oils the described process consisting in introducing hydrocarbon oil before evaporation or dissociation into the lower part of a molten metal bath in a retort, collecting the resulting vapors and gases in the upper part of 90
 the retort, conveying them away from the retort through an upwardly extending duct, condensing the vapors, continuously supplying to and withdrawing from the surface of 95
 the bath a layer of the heavy fractions and unvaporized hydrocarbons, among them the condensate and backflow from said duct, which layer holds the carbon impurities in suspension, and regulating the supply of the 100
 material to form the layer as required.

7. The process of converting hydrocarbon oil into more volatile products, which consists in submerging said hydrocarbon oil for evaporation and decomposition beneath a 105
 molten metal bath contained in a retort, protecting the hydrocarbon oil from the effects of heat sufficient to decompose until delivered beneath the bath, withdrawing the resulting vapors and gases from the upper part 110
 of the retort, conveying them away and condensing them, constantly supplying hydrocarbon oil on the surface of said molten metal bath to float the carbon formed, continuously withdrawing hydrocarbon oil and 115
 the carbon from the said supply, separating therefrom carbon resulting from the decomposition, and returning all of the oil freed from carbon to the retort for submergence beneath the molten metal bath. 120

8. The process of breaking up the heavy products of petroleum, and the like, into more volatile products, which consists in introducing the petroleum into the lower portion of a plurality of chambers depending 125
 from and forming part of the bottom of a still, maintaining a protecting medium for the petroleum whereby it is unaffected by the heat prior to its admission directly into the lower portions of said chambers, main- 130

taining in said chambers and on the said bottom of the still a bath of non-evaporable molten metal, and maintaining on the surface of said metal on the bottom of the still 5 a layer of hydrocarbon oil which sustains the carbon formed, permitting the material under treatment to pass through the molten bath and through said layer of hydrocarbon oil, permitting the resultant vapors to escape and condense, and removing hydrocarbon oil from the surface of the bath.

9. In the cracking of hydrocarbon oils, the described process consisting in passing the oil to be treated through a molten metal bath 15 in a retort, collecting the resulting vapors and gases in the upper part of the retort, conveying them away and condensing them, and continuously supplying to and continuously withdrawing from the surface of the 20 bath a layer of the heavy fractions and unvaporized hydrocarbons which holds the carbon impurities in suspension, and continuously separating the carbon therefrom.

10. The process of breaking up the heavy 25 products of petroleum, and the like, into more volatile products, which consists in introducing the petroleum into the lower portions of a plurality of chambers depending from and forming part of the bottom of a 30 still, maintaining a protecting medium for the petroleum whereby to prevent decomposition prior to its admission directly into the lower portions of said chambers, maintaining in said chambers and on the said 35 bottom of the still a bath of nonevaporable molten metal, and maintaining on the surface of said metal on the bottom of the still a layer of hydrocarbon oil, which sustains the carbon formed, permitting the material 40 under treatment to pass through the molten bath and through said layer of hydrocarbon oil, permitting the resultant vapors to escape and condense, removing hydrocarbon oil from the surface of the bath, separating the 45 carbon from the latter, and returning to the still the oil from which the carbon has been removed.

11. In an apparatus for converting hydrocarbon oils into more volatile products, the 50 combination of a retort containing a molten metal bath, said retort having adjacent its top an opening for vapors, a condenser for receiving said vapors, conduits leading into the retort and having an outlet adjacent the 55 bottom of the retort for submerging said hydrocarbon oils beneath the molten bath, means for maintaining a body of hydrocarbon oil on the surface of the molten metal bath, and said retort having a continuous outflow 60 for said body of hydrocarbon oil, means without the retort but associated therewith for separating from the hydrocarbon oil the carbon resulting from the decomposition, and means for operatively connecting said separating means with the conduits whereby the 65

body of oil from which the carbon has been removed is returned for submergence beneath the metal bath in the retort.

12. An apparatus for converting hydrocarbon oils into more volatile products, comprising a retort having depending from the bottom thereof a plurality of chambers, a bath of non-evaporable metal filling said chambers and overlying the bottom of the container, a hydrocarbon oil inlet conduit 70 leading to each chamber and having a discharge outlet for the oil arranged at a point adjacent the lower end of said chambers and opening directly into said bath of metal, a protecting covering for said conduits to prevent premature decomposition of the contained hydrocarbon oils, means for imparting to the metal constituting the bath heat sufficient to decompose the hydrocarbons, and means for removing the formed carbon sediment accumulating upon the surface of the bath.

13. In the cracking of hydrocarbon oils, the described process consisting in passing the oil in a substantially unvaporized and 90 undissociated state upwardly through a molten metal bath in a retort, collecting the resulting vapors and gases in the upper part of the retort, conveying them away and condensing them, and continuously supplying 95 directly to and continuously withdrawing from the surface of the bath a layer of the heavy fractions and unvaporized hydrocarbons which holds the carbon impurities in 100 suspension, and continuously separating the carbon therefrom.

14. The process of cracking hydrocarbon oils, consisting in passing the hydrocarbon oil before substantial evaporation or dissociation through a molten metal bath in a retort, continuously supplying directly to the upper surface of such bath and continuously withdrawing from said surface, a layer of unvaporized hydrocarbons which holds the 105 carbon impurities in suspension, and separating the carbon impurities.

15. The process of converting hydrocarbon oils into more volatile products, which consists in submerging the hydrocarbon oil, before evaporation or dissociation, beneath a 115 molten metal fluid maintained at a sufficient temperature to decompose said hydrocarbon oil as it passes upwardly through said fluid, withdrawing the resultant vapor from a point above the molten fluid, maintaining on 120 the surface of the bath a layer of hydrocarbon oil, by introducing said oil from the outside directly to the surface of said bath, whereby the carbon produced in the treatment is mixed therewith, and continuously 125 removing the unvaporized hydrocarbon which holds the carbon impurities in suspension.

16. An apparatus for converting hydrocarbon oils into more volatile products, com- 130

- prising a retort having a bath of non-evap-
orable metal, a conduit adapted to introduce
the hydrocarbon oil without evaporation
and dissociation at the lower portion of said
bath of metal, means for imparting to the
metal constituting the bath heat sufficient to
decompose the hydrocarbons, means leading
through the wall of the retort to directly
supply to the upper surface of said bath a
layer of hydrocarbon oil, and means causing
the continuous discharge of the formed car-
bon sediment accumulating upon the surface
of the bath.
17. In an apparatus for converting hydro-
carbon oils into more volatile products, the
combination of a retort having therein a
molten metal bath, conduits constructed and
arranged to deliver the hydrocarbon oil to be
treated at a point adjacent the bottom of said
bath, without said hydrocarbon oil becoming
vaporized or dissociated, said retort having
adjacent the top of said bath an inlet, and
a constantly open outlet, means for continu-
ously introducing through said inlet hydro-

carbon oil to form a layer on said bath which 25
finds a continuous exit through said outlet,
and means for removing the vapors formed.

18. In an apparatus for converting hydro-
carbon oils into more volatile products, the
combination of a retort having therein a 30
molten metal bath, conduits constructed and
arranged to deliver the hydrocarbon oil to
be treated at a point adjacent the bottom of
said bath without said hydrocarbon oil be-
coming vaporized or dissociated, means for 35
maintaining on the surface of the said bath
a moving body of hydrocarbon oil, the said
retort having an inlet in one wall above said
surface for said oil to constitute the layer,
and an outlet for the removal of hydrocar-
bon oil from the surface of the bath, and
means for separating the hydrocarbon from
the latter.

In witness whereof we have hereunto
signed our names.
